UNITED STATES PATENT OFFICE

JOHN WILLIAM COX, DECEASED, LATE OF NEWARK, NEW JERSEY, BY GEORGE A. S. COOPER, ADMINISTRATOR, OF NEWARK, NEW JERSEY, ASSIGNOR TO THE NESTLE-LEMUR COMPANY, OF NEW YORK, N. Y., A CORPORATION OF OHIO

HAIR-WAVING MACHINE

Application filed January 6, 1932. Serial No. 584,984.

This invention relates to improvements in hair-waving machines and has particular reference to an apparatus employed in the process of permanent waving.

5 An object of the invention is to provide a simple and practical machine wherein the construction of the various instrumentalities constituting the same is such as to greatly facilitate their assembly.

10 Another object is to materially reduce the effect of heat radiation by including, as a part of the machine, a fan which will direct a cooling current of air on to the heaters of the machine while the same are in operation, thereby overcoming, to a large extent, the inconveniences to which a person is subjected when the hair is being waved.

15 A further object is to provide an improved device for supporting the cord of a heater whereby the same may be adjusted relative to the frame from which the heater is suspended, and frictionally held in its adjusted positions.

20 A still further object is to provide an efficient and durable device for supporting the heater cord in a manner which will prevent accidental detachment of the cord from the device and through the medium of which excess strain upon said cord, occasioned by 25 pulling the same in certain directions, will be relieved.

25 Still another object is to increase the efficiency of control of the machine by assembling various control instrumentalities in one 30 compact unit and mounting the same conveniently within reach of the operator.

The above and other objects will appear more clearly from the following detailed description, when taken in connection with the 35 accompanying drawings, which illustrate a preferred embodiment of the inventive idea.

In the drawings—

40 Figure 1 is a side elevation of the machine, partly in section;

45 Figure 2 is a top plan view of the support-

ing head and the spreader frame from which the heaters are suspended;

Figure 3 is an enlarged side elevation of the supporting head and associated instrumentalities, parts being broken away and shown in section;

Figure 4 is a plan view, substantially on the line 4—4 of Figure 3;

Figure 5 is a fragmentary sectional view of the interior of the shell or casing forming a part of the supporting head;

Figure 6 is a fragmentary exterior view of said shell or casing, illustrating some of the elements of separable connectors arranged thereon;

Figure 7 is a fragmentary horizontal section through the shell or casing and taken substantially on the line 7—7 of Figure 6;

Figure 8 is a transverse section on the line 8—8 of Figure 7;

Figure 9 is a similar section on the line 9—9 of Figure 7;

Figure 10 is an enlarged side elevation, partly in section, of one of the heater cord-supporting devices employed in connection with the machine;

Figure 11 is a plan view of the device illustrated in Figure 10;

Figure 12 is an enlarged elevation, partly in section, of a control unit supported upon the standard of the machine;

Figure 13 is a plan view of a connector plug utilized for electrically connecting a heater to one of the connecting elements of the annular row supported upon the head of the machine;

Figure 14 is an end elevation of said plug;

Figure 15 is a plan view of one of the complementary sections of said plug, illustrating the prongs or tips positioned therein prior to the assembly of said sections; and

Figure 16 is a plan view of the other of the sections of the plug, illustrating the arrangement of grooves and recesses therein.

In its preferred form, the invention is

shown as comprising a standard 20 having an upper angular section 21 forming an extension by means of which the height of the standard may be varied, a set screw 22 or any other means being employed to secure the section 21 in its adjusted positions. Adjacent the upper free end of the section 21, the same is provided in its under surface with an opening 23 and contiguous to this opening there is secured to said section, by means of rivets 24, a casting 25. This casting forms a part of a head utilized to support various elements of the machine and said head further includes a shell or casting 26, preferably of cylindrical formation, which is detachably secured to the casting 25 by means of screw bolts 27 inserted into the shell upwardly from the bottom thereof so that, when the detachable bottom plate 28 of said shell is removed, ready access may be had to the bolts 27 to unscrew them from the casting 25 and thus detach the shell along with all of the other elements supported thereby. Screws 29 are threaded into the heads of the bolts 27 to detachably connect said bottom plate to its shell.

A circular spreader frame 30 is utilized to support a plurality of heaters 31, which may be of any conventional type employed in permanent hair waving and the cords 32 of which are suspended from supporting devices generally indicated by the numeral 33, which are arranged about the periphery of the frame 30 in staggered relation, as best illustrated in Figure 2. These supporting devices 33 will be later described in detail. In order to mount the frame upon the head of the machine, intersecting and radially extending arms 34 (Figure 4) for the frame 30 are provided and the inner portions of said arms are extended through notches 35 formed in the upper peripheral edge of the bottom plate 28.

Means are provided in connection with the invention for directing a downward current of air on to the heaters 31 so as to reduce the effect of heat radiation and thereby render the operation of waving the hair more comfortable to the subject. This means comprises a fan 36 and its motor 37, the casing of which is detachably secured, by screws 38, to the bottom plate 28 of the head from which said fan depends. A protective cage 39 is provided for the fan 36 and in this cage 55 there is mounted a conical deflector 40 disposed in the path of the current of air created by the fan 36 and thereby adapted to divert said current of air outwardly and downwardly toward the heaters 31 which 60 are arranged in encircling relation to the fan.

The electrical connections for supplying current to the various heaters 31 will now be described and in this connection it is to be noted that each heater is separably connected

to a common source of current supply. To this end, an annular insulating band 41 is suitably secured in encircling relation upon the shell 26 and two conductors 42 are extended around said band from within the shell 26, an opening 43 (Figure 5) being formed in the shell for this purpose. At the point where the conductors 42 extend through said opening they also pass through an insulation block 44 (Figure 9) which is secured to the shell 26 and against the band 41 by means of screws 45, an insulating plate 46 being fastened to the interior surface of the shell by the nuts of the screws 45. This block 44 is, in reality, a blank constructed similarly to the annular row of connecting members, presently to be described in detail, so as to present uniformity of appearance to said row when the machine is completely assembled. On the portions of the conductors 42 which extend exteriorly of the shell 26 there are mounted, by soldering or otherwise attaching, a plurality of sleeve-like contact elements 47 arranged in spaced groups, a pair of vertically aligned elements constituting each group when the conductors are properly arranged about the shell. In assembling the supporting head and associated elements of the machine, the conductors 42 are first held against the insulating band 41 adjacent the opening 43 and one of the connecting socket members 48 forming part of a separable connector is then mounted upon the first pair of contact elements 47 adjacent said opening, said member 48 being provided therethrough with two openings 49 for receiving said elements. A third intermediate opening 50 is provided in the member 48 and through this opening there is extended a screw member 51, the inner end of which projects through aligned openings 52 formed in the shell 26 and insulating band 41. With the bottom plate 28 of the shell removed at this time, a nut 53 is threaded upon the inner end of the screw 51 and engaged directly with the inner surface of said shell. The screw member 51 is provided with a socket 54 to receive one of the prongs of the plug member of the separable connector previously referred to and which will later be described in detail, and constitutes a ground connection whereby the heater which is joined to the member 48 will be grounded through the machine. The vertical or side edges of the connecting members 48 are all tapered, as best shown in Figure 7, so that when the next member in the annular row is mounted in position, the same will fit snugly against the adjacent member. After the first member 48 has been secured in position in the manner just described, the conductors 42 are held so that the next pair of contact elements 47 are in vertical alignment and the second member 48 is then mounted thereon. This operation is continued around the shell 125

26 until the required number of connecting members 48 for the various heaters are in position. When this has been done, there is still left a blank space in the annular row next adjacent the insulation block 44 and on the upper side thereof, as viewed in Figure 7. This space is utilized for the reception of another socket member 55 for connecting the motor 37 of the fan to the source of current through the conductors 56, which also extend through the opening 43 in the shell 26. The socket member 55 is illustrated in detail in Figure 8 and is shown as provided with openings 57 for receiving a pair of the contact elements 47 and a third opening 58 through which a screw 59 is passed, the inner end of said screw projecting through the shell 26 and a nut 60 being threaded upon said screw and against the insulating plate 46. The mounting of the various socket connecting members having been completed, the bottom plate 28 of the supporting head may now be secured in position by means of the screws 29, following which the motor and its fan are fastened to said bottom plate by the screws 38.

The cords 32 of the heaters, each of which contains three conductors, are electrically connected to plug members generally indicated by the numeral 61 (Figure 2) and shown in detail in Figures 13 to 16. Each of these plug members is common to two cords 32 and is adapted to be plugged into one of the connecting members 48. Specifically, the plug member 61 comprises a pair of complementary sections 62, each of which is provided upon its interior surface and adjacent the longitudinal edges thereof with prong-receiving grooves 63 and 64 and an intermediate prong-receiving groove 65. At the inner ends of each of the grooves 63 and 65 there is formed an enlarged circular recess 66, while in the bottom of the groove 64 there is provided a small circular recess 67. Three prongs 68, 69 and 70 are provided for making the various connections, the intermediate prong being used as a ground connection for the third wire of each of the cords 32 joined to the plug member, said prong 69 being insertable into the socket 54 of the screw 51 which is grounded to the shell 26. At the inner end of each of the prongs the same has mounted thereon a terminal screw 71, to each of which is connected two of the conductors of the pair of heater cords to which the plug member is common. When assembling the plug, two of the prongs, such as the prongs 68 and 69, are laid in their respective grooves with the heads of the screws 71 engaging in the enlarged recesses 66, while the third prong 70 is positioned in its groove with the small end of the screw 71 extending into the recess 67 of the groove 64 so as to prevent longitudinal shifting of the prong in its groove. The grooves of each section 62 are slightly larger than the portions of the prongs which they receive in order to permit of a certain amount of lateral movement of the prongs, after the plug has been assembled, whereby they may be more easily aligned with and inserted into the openings in a connecting member 48. After positioning the prongs in one of the sections 62 as described, the other section of the plug may be placed over the first-named section and then secured thereto by screw fasteners 72 extending through the sections. By making the two sections 62 of exactly the same construction, it will be apparent that the enlarged recess 66 adjacent the edge of the section 62 not containing the prongs will receive the head of the screw 71 carried by the prong 70, while the small recess 67 in the groove 64 will receive the small end of the screw carried by the prong 68, the inner recesses 66 of the two sections being then opposed. With these two latter recesses opposed, other means than the small recess 67 must be provided in order to prevent excessive longitudinal or inward shifting of the prong 69 in its groove. To this end, said prong is provided with an annular flange 73 which engages a shoulder 74 formed in the groove 65 of each of the sections 62.

In order to suspend the cords 32 from the frame 30 in such a manner as to relieve strain upon the cords by pulls thereon in different directions when manipulating the heaters, and also to permit of vertical adjustments of the cords and, consequently, of the heaters, the devices 33 are mounted in staggered relation on the inner and outer faces of the annular frame 30 and extend laterally in the plane thereof. Each of these devices, as shown in detail in Figures 10 and 11, is in the form of a gimbal and comprises a substantially U-shaped bracket 75 made of resilient material so as to permit of relative lateral movement of the arms of the bracket. The bight of this bracket is connected to the frame 30 by a swivel 76 in order to permit of a rocking or swinging movement of the bracket about an axis which extends radially of the frame. Adjacent the outer ends of the arms of the bracket 75, the same has mounted therein a pair of rocking cooperating cord-engaging and clamping members 77 and 78, each being of arcuate formation and having a trunnion 79 extending through an opening in the adjacent arm of said bracket. The two members 77 and 78 are held in cooperative relation, when a cord is not engaged therewith, by a pin 80 on the former member extending into a recess 81 in the latter member. The outer portions of the members 77, 78 are curved away from each other to provide a flared entrance 82 into which the cord 32 is inserted when positioning the same between the clamping members. As this is done, the members will be

permitted to spread apart, owing to the resiliency of the bracket 75, and when the cord is in position said members will come together in cooperative relation to frictionally grip the cord and thereby hold it in adjusted position.

The control mechanism for the heaters and the fan are assembled in a unitary structure comprising a casing 82 fixed in any suitable manner upon the section 21 of the standard 10 and containing therein a time switch, generally indicated by the numeral 83 and being of any well-known design, which will control the automatic shutting off of the current to the heaters 31 at the end of a predetermined 15 interval of time. This time switch includes a dial 84, a portion of which projects from the casing 82 (Figure 1) so as to permit of a manual adjustment thereof to set the mechanism for the desired interval of time that the current is to flow to the heaters. After this setting is accomplished, the switch arm 85 is thrown to close the circuit to the heaters from the source of supply which is connected to the time switch through a three-wire conduit 20 25 and plug 87, one of the wires of this conduit being a ground connection joined to the casing 82 at 88. The control for starting the motor 37 and regulating the speed of the fan 36 is a rheostat 89 mounted within the casing 30 35 40 45 50 55 60 65 70 75 80 85 90 95 100 105 110 115 120 125 130 135 140 by said head, and a plurality of heaters suspended from said frame and joined to said connecting members.

11. In a hair-waving machine, a supporting head including a shell, electrical conductors carried by and extending around said shell, contact elements carried by said conductors and arranged in groups thereon, a separable connector mounted on each group of contact elements, means on one member of each connector extending through said shell for attaching said member thereto, and heaters joined to the other members of said separable connectors.

12. In a hair-waving machine, a supporting head including an annular shell, electrical conductors carried by and extending circumferentially around said shell and carrying contact elements arranged in groups thereon, a separable connector supported by each group of contact elements and disposed in an annular row about said shell, and heaters joined to said separable connectors.

13. In a hair-waving machine, a frame, and heater cord-supporting means carried by said frame and having a swivel connection therewith.

14. In a hair-waving machine, a frame, and a gimbal carried by said frame and through which a heater cord is slidable.

15. In a hair-waving machine, a frame, a heater cord-supporting device carried by said frame and through which a cord is slidable, said device including a bracket having a rocking connection with said frame, and cooperating cord-holding elements movably mounted in said bracket.

16. A heater cord-supporting device for use on hair-waving machines, comprising a bracket, and opposed cord-engaging elements mounted to rock on said bracket and having lateral movements relative to each other when a cord is inserted therebetween or withdrawn from engagement therewith.

17. A heater cord-supporting device for use on hair-waving machines, comprising a bracket, and opposed cord-engaging elements mounted to swing on said bracket and having lateral movements relative to each other when a cord is inserted therebetween or withdrawn from engagement therewith, adjacent portions of said elements combining to form a flared entrance for the insertion of the cord.

18. A heater cord-supporting device for use on hair-waving machines, comprising cooperating cord-engaging elements between which a cord is extended, a resilient mounting on which said elements have angular movement and by which the same are held in frictional engagement with said cord, and means to support said mounting for turning movement about an axis transverse to the axis of motion of said cord-engaging elements.

19. In a hair-waving machine, a frame, and heater cord clamping and guiding means

mounted on said frame so as to have angular movement on two different axes disposed at right angles to each other, said means adapted to yieldingly clamp a heater cord to automatically hold it at rest and at the same time 70 permit it to be drawn therethrough by virtue of the yielding capacity thereof.

20. In a hair-waving machine, a frame, and heater cord clamping and guiding means mounted on said frame so as to have angular 75 movement on two different axes disposed at right angles to each other, said means adapted to yieldingly clamp a heater cord to automatically hold it at rest and at the same time permit it to be drawn therethrough by virtue 80 of the yielding capacity thereof, said means being constructed and arranged so as to open for lateral insertion therein and also removal therefrom of a heater cord by forcible lateral movement thereof.

21. In a hair-waving machine, a supporting head including a shell, electrical contact elements arranged about said shell, and a plurality of detachable socket members connected to said contact elements, said socket 90 members being disposed in juxtaposed and abutting relation to each other, in a substantially unbroken row.

22. In a hair-waving machine, a supporting head including a shell, electrical contact 95 elements arranged about said shell, and an annular row of detachable socket members extending about said shell and connected to said contact elements, each socket member in said row being tapered and having its tapered sides contacting those of adjacent socket members.

23. In a hair-waving machine, a standard, heaters supported thereby, a fan also carried by said standard, a control unit attached 105 to said standard and including a casing, a time switch therein connected to said heaters, a rheostat also in said casing for controlling said fan, and a voltmeter detachably mounted upon the casing of said unitary structure.

24. An electrical connector, comprising separable complemental sections, each having a plurality of prong-receiving grooves, and also having enlarged recesses at the inner ends of two adjacent grooves, the remaining 110 groove in each section having a small recess formed therein intermediate its ends, one of said enlarged recesses of one of said sections being opposed to the small recess in the other section when the sections are assembled, 120 prongs in said grooves, and a terminal screw for each prong having its headed end engaged in one of said enlarged recesses, with the opposite ends of certain of the screws engaged in the adjacent small recesses.

25. A hair waving machine, comprising a standard, a supporting head including a shell, electrical heater connections carried by said head, fastening elements for detachably securing said shell to said standard, a re- 130

movable bottom for said shell, other fastening elements engageable with the first-named fastening elements to detachably connect said bottom to said shell, a spreader frame supported on said bottom, and a plurality of heater elements suspended from said frame and joined to said electrical heater connections.

In testimony whereof, I have affixed my
10 signature as administrator of the estate of
JOHN WILLIAM Cox, deceased.

GEORGE A. S. COOPER,
*Administrator of the Estate of John William
Cox, Deceased.*
